United States Patent Office

Des. 194,409
Patented Jan. 15, 1963

194,409

JUG

Richard L. Platte, Ann Arbor, Mich., assignor to
Hoover Ball and Bearing Company

Filed July 23, 1962, Ser. No. 71,008

Term of patent 14 years

(Cl. D58—5)

FIGURE 1 is a side elevation of a jug, showing my new design;

FIGURE 2 is a rear elevational view thereof;

FIGURE 3 is a front elevational view thereof; and

FIGURE 4 is a top plan view thereof.

The dominant features of my design reside in the portions shown in full lines.

I claim:

The ornamental design for a jug, as shown and described.
